UNITED STATES PATENT OFFICE.

ALOYSIUS NIEMCZEWSKI, OF ELMIRA, NEW YORK.

FLOWER STAND.

Application filed June 22, 1922. Serial No. 570,136.

To all whom it may concern:

Be it known that I, ALOYSIUS NIEMCZEWSKI, a citizen of the United States of America, residing at Elmira, in the county of Chemung and State of New York, have invented certain new and useful Improvements in Flower Stands, of which the following is a specification.

This invention relates to certain new and useful improvements in flower stands, and has particular reference to a stand for supporting potted plants with a drain device associated with the stand to prevent the overflow of water from the stand when the plants are being watered.

The primary object of the invention resides in the provision of a stand especially designed for growing flowers in earthenware pots with a drain device associated with the table or stand top positioned above a waste receptacle supported beneath the stand to prevent the overflow of water from the stand during the watering of the plants.

The invention further embodies in a flower stand of the type above set forth the provision of a rotatable table top for purposes of varying the positions of plants with respect to the light from windows.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a vertical sectional view of a flower stand constructed in accordance with the present invention, showing the centrally positioned drain spout carried by the table top extending into the apertured cup secured to the upper end of the stand and the drain receptacle, shown by dotted lines, supported on a platform intermediate the upper and lower ends of the stand legs,

Figure 2 is a fragmentary top plan view with the tray upon the table top partially broken away to show the drain spout,

Figure 3 is a vertical sectional view of a modified form of the invention showing the drain spout detachably connected to the table top and the tubular member carried by the stand for supporting the table top,

Figure 4 is a horizontal sectional view taken on line IV—IV of Fig. 3,

Figure 5 is a detail sectional view showing a portion of the upper end of the stand disclosed in Fig. 3, and the table top and spout associated therewith,

Figure 6 is a front elevational view of a modified form of stand with the base portion thereof embodying a caster supported platform,

Figure 7 is a side elevational view of the table, taken at right angles to the showing in Fig. 6,

Figure 8 is a horizontal sectional view of the table shown in Figs. 6 and 7,

Figure 9 is a side elevational view of another modified form of stand,

Figure 10 is a perspective view of the apertured cup associated with the drain spout, and

Figure 11 is a perspective view of the tray removed from the table top.

Referring more in detail to the accompanying drawings, and particularly to Figures 1 and 2, there is illustrated a flower stand embodying supporting legs 1 outwardly bowed as at 1^a adjacent the upper ends thereof with a platform 2 supported by the legs upon which a drain receptacle 3, shown by dotted lines is placed. The upper ends of the legs 1 are connected by a plate 4 having the central opening 5 therein for purposes presently to appear.

A table top 6 having a marginal upwardly directed rim or flange 7 is supported on the plate 4 and carries a centrally positioned depending drain spout 8 projecting through the opening 5 in the plate 4 and materially spaced from the side walls of said opening as indicated in Fig. 1. A bell-shaped cup 9 provided with a drain opening 10 in the lower end thereof, carries at its upper end a circular collar or flange 11 that is received in the opening 5 and frictionally engages the wall of said opening and is suitably secured as by welding, to the table top 6. A disk tray 12 having spaced supporting feet 13 is placed upon the table top 6 overlying the opening 5 and drain spout 8 for the purpose of hiding the drain from view.

As shown in Fig. 1, by dotted lines, potted plants 14 are placed on the table top 6 and the tray 12, and waste water therefrom will be delivered to the drain spout 8 and apertured cup 9 for discharging into the waste

receptacle 3 in an obvious manner. With a device of this character, it will be seen that unusual care in the watering of potted plants is not required, as the waste water therefrom is directed into a receptacle intended therefor.

In the form of the invention shown in Figs. 3 to 5, the legs 15 of the stand are perpendicular throughout their length, and support a platform 2^a adjacent the lower end thereof. The upper ends of the legs 15 carry inwardly directed brackets 16 that support a tubular member 17. The table top 6^a has a central opening 18 formed therein that is surrounded by a depending spout 8^a that carries an outwardly directed flange 19 at its upper end for detachable engagement with the table top 6^a as indicated at 20. The waste water gathering upon the table top 6^a is delivered through the spout 8^a into a suitable receptacle placed upon the platform 2^a, the table top 6^a and drain spout 8^a carried thereby being bodily removable from the tubular supporting member 17.

Another form of the invention is shown in Figs. 6, 7 and 8, the same embodying a pair of outwardly arched or reversely curved side legs 21 that are connected at their lower ends to a block 22 upon a base platform including a cross arm 23 and transverse legs 24 that are supported by rollers or casters 25. The upper ends of the legs 21 are associated with a plate 4 and table top 6 as described in connection with the preferred form of the invention shown in Figs. 1 and 2. A waste receptacle is placed upon the block 22 and water draining from the apertured cup 9 is delivered thereto. In the form of the invention shown in Fig. 9, a stand embodies perpendicular corner legs 26 with a platform 27 secured thereto at a point spaced upwardly of the lower end, the remaining elements thereof being identical with the construction shown in Figs. 6 and 7.

From the above detail description of the device, it is believed that the construction and operation thereof will at once be apparent, it being noted that waste water draining from the flower pot 14 is received upon the table top member and delivered through the spouts to waste receptacles supported on the platform.

While there are herein shown and described the preferred embodiments of the present invention, it is nevertheless to be understood that minor changes may be made in the invention without departing from the spirit and scope thereof as claimed.

What is claimed as new is:—

1. In a flower stand of the type described, supporting legs, a table top rotatably carried thereby and having a centrally positioned depending drain pipe, and a platform carried by the stand for supporting a waste receptacle beneath the drain pipe. 65

2. In a flower stand of the type described, supporting legs, a table top rotatably carried thereby and having a centrally positioned depending drain pipe, a platform carried by the stand for supporting a waste receptacle beneath the drain pipe, and an apertured cup enclosing the drain pipe and secured to the table top. 70 75

3. In a flower stand of the type described, supporting legs, a table top carried thereby and having a centrally positioned depending drain pipe, a platform carried by the stand for supporting a waste receptacle beneath the drain pipe, and a tray having supporting feet resting upon the table top and overlying the drain spout. 80

4. In a flower stand of the type described, supporting legs, a platform carried by said legs adjacent the lower ends thereof, a tubular supporting member carried by the upper ends of said legs, a table top removably supported within the tubular member, and a drain spout carried by the table top extending through said tubular member. 85 90

5. In a flower stand of the type described, supporting legs, a platform carried by said legs intermediate the ends thereof, a plate connecting the upper ends of said legs and having a central opening therein, a table top resting upon said plate, a depending centrally positioned drain spout carried by the table top extending through said plate opening and spaced from the walls thereof, and a flanged apertured cup enclosing the drain spout with the flange thereof frictionally engaging the side walls of the plate opening. 95 100 105

6. In a flower stand of the type described, supporting legs, a platform carried by said legs intermediate the ends thereof, a plate connecting the upper ends of said legs and having a central opening therein, a table top resting upon said plate, a depending centrally positioned drain spout carried by the table top extending through said plate opening and spaced from the walls thereof, a flanged apertured cup enclosing the drain spout with the flange thereof frictionally engaging the side walls of the plate opening, and a tray supported on the table top above the drain spout. 110 115

In testimony whereof I affix my signature.
ALOYSIUS NIEMCZEWSKI.
